CONVERTIBLE HAMMER MILL AND SILAGE CUTTER

Frank W. Brannon, deceased, late of Luthersville, Ga., by James C. Brannon, administrator, Moreland, Ga.

Application April 7, 1937, Serial No. 135,572

5 Claims. (Cl. 83—11)

Generically this invention relates to feed mills, but it more particularly is directed to a convertible hammer mill and silage cutter.

One of the principal objects of this invention 5 is the provision of an improved rotor structure designed to permit the materials to be ground to be more readily delivered to all parts of the rotor and including series of swinging hammers which latter operate more efficiently than the solid or 10 notched type heretofore in use since a single hammer can be replaced more easily and at less cost than the entire section.

A further object of this invention is the provision of a shredder head of rigid hammer construction designed to break up the materials to be ground as they enter the rotor and direct them 15 upwardly in the path of the finishing or swinging hammers, thereby greatly increasing the capacity of the machine without increasing the power 20 requirements.

Another object of this invention is the provision of a larger screen area comprising removable screens designed to give increased capacity and decreased clogging of the machine and at 25 the same time permitting instant removal of the screens to convert the machine from a hammer or feed mill into an ensilage machine.

Another object of this invention is the provision of blower or fan blades adjustable with respect to the motor to vary the air supply in accordance with the particular operating requirements.

A still further object of this invention is the provision of a machine of this character having 35 a sectional casing hinged so that the upper portion may be moved to render the rotor accessible and permit ready removal of the screens, said casing having a horizontal discharge for the milled material which allows a larger screen area 40 than the vertical discharge type heretofore in use.

With these and other objects in view, which will become apparent as the description proceeds, the invention resides in the construction, 45 combination and arrangement of parts, herein-after more fully described and claimed, and illustrated in the accompanying drawings, in which like characters of reference indicate like parts throughout the several figures, of which:

50 Fig. 1 is a side elevation of my improved mill with the conveyor omitted.

Fig. 2 is a fragmentary end view of the device and side view of a portion of the feed conveyor.

Fig. 3 is a fragmentary vertical sectional view of 55 the device partly in elevation.

Fig. 4 is a vertical sectional view taken on the line 4—4 of Fig. 3.

The machines of this general type have proven deficient by being so constructed as to obstruct and prevent the material readily penetrating all parts of the rotor as it is fed thereto, having reduced screen area, inaccessibility of the interior construction, not readily convertible from one type of mill to another, and having limited capacity, and it was to overcome such deficiencies by 10 providing a greater screen area thereby increasing the capacity of the machine without increasing the power requirements, an improved swinging hammer structure, a unique shredder head comprising a rigid hammer structure, a unique 15 shredder head comprising rigid hammers of varying lengths, and a large diameter rotor structure designed to operate at a comparatively low speed thereby tending to reduce belt friction and enabling the use of an ordinary farm tractor or engine without the employment of a speed jack, the 20 low speed being made possible by the large diameter rotor which gives high peripheral speed at a low R. P. M. of the drive shaft, and including adjustable fan blades, that the device was 25 designed forming the subject matter of this invention.

In the illustrated embodiment characterizing this invention there is shown a housing or casing A, a ground material receiving hopper B, and 30 rotor structure C.

The casing A comprises a pair of, in the present instance, rectangular side members 1 formed with end flanges 2 and bottom flanges 3. Suitably mounted intermediate sides 4 and constituting the end and bottom walls of the lower half of the casing is a semi-circular member 4 secured and supported by bolts 5 connecting the respective sides 1 adjacent the outer surface of said member 4 and uniting said members and sides 35 into a unitary structure. The flanges 3 of sides 1 are adapted to seat on respective runner supports 6 to which they are secured by bolts 7 or other fastening means. Said supports 6 extend substantially beyond one end of the casing for a 40 purpose hereinafter appearing.

A semi-circular top member 8 is adapted to form the upper half of the casing and when closed forms continuations of sides 1 and member 4, said member 8 is formed at its rear edge 50 with rearwardly extending spaced ear members 9 suitably secured to the respective sides of said member 8 and also suitably secured intermediate said ears is a reinforcing angle member 10. The free ends of said ears 9 are apertured to receive 55

hinge bolt 11 extending therethrough and through the apertured ends of hinge posts 12 secured to sides 1 adjacent their rear edges by bolts 13 or in any suitable manner. Bolted or otherwise secured to member 4 adjacent its upper front edge is apertured lug member 14 adapted to receive the hook or loop end 15 of lock bolt 16 adapted to engage the bifurcated end 17 of angle member 18 bolted or otherwise suitably secured to the lower front edge of casing section 8, the free end of said bolt 16 threadedly carries nut 19 adapted to lock the lower section and section 8 of the casing in closed position as will be apparent. Said bolt is readily removable to permit opening of said member 8 by handle 20 bolted or otherwise suitably secured to said member as will be apparent. A substantially triangular opening 21 is formed in one side of top portion 8 of the casing through which the material to be milled is fed, as will hereafter more fully appear.

Suitably connected to said casing A at the bottom, thereof is discharge blower pipe or conduit (a) formed with a horizontal discharge section 22, a vertical section 23, and a substantially horizontal section 24 with its upper end extending through opening 25 in the side wall of hopper section 26. A funnel like portion 27 is formed at its lower end with discharge opening 28 and at its upper end with flange 29 adapted to embrace the lower edge of hopper section 26 to which it is suitably secured, said member 27 constituting the bottom section of hopper B as will be apparent. Hopper B is supported on opposite sides by angle iron supports 30 having their upper ends bolted or otherwise suitably secured thereto as at 31 and their lower ends bent to form feet 32 adapted to seat on and secured to the ends of runners 6 by bolts 33. Said hopper is further supported by brace members 34 with their lower ends mounted on bolt 11 connected to the respective supports 30 by bolts 35 and extending upward at an angle therefrom with their upper ends secured to flange 29 by bolts 36.

At the bottom of casing A, member 4 is formed with an opening 37 adapted to receive the end of section 22 of blower pipe (a) and suitably mounted in said casing is a screen (b) extending from the upper edge of the end of pipe 22 as at 38 spaced from the inner surface of member 4 gradually extending toward the inner surface of top section 8 and intercepting said surface as at 39 thereby forming the gradually enlarged passage 40 from 38 to 39 from which point horizontal discharge section 22 of pipe (a) forms a continuation of said passage. Said screen (b) is divided into a lower section 41 and upper section 42, the latter being suitably mounted in upper casing section 8 as will be clear without further discussion. The screen section (b) really forms a continuation of wall member 4 with respect to rotor C which is mounted therein as will hereinafter more fully appear.

Secured to the respective sides 1 adjacent their upper edges by bolts 43 is an angle iron support 44, on the laterally extending flange 45 of which is mounted ball bearing 46 secured thereto by bolts 47.

A shaft 48 is journalled in bearings 46 and mounted on which, keyed or otherwise suitably secured thereto, is rotor C comprising a solid disk 49 and a spaced ring member 50. The upper edge of side 1 at the lower edge of opening 21 is suitably formed to constitute a cutting edge 51 adapted to cooperate with cutter blades 52 bolted or otherwise secured to ring member 50 and flange

53, to cut the material as it is fed through opening 21 as will directly more fully appear.

Mounted on shaft 48 adjacent the inner surface of disk 49 is a flange hub member 54 keyed or otherwise secured to said shaft and adapted to reinforce disk 49 to which it may be bolted or otherwise secured. Mounted on said shaft intermediate knife 52 and hub 54 are the rigid hammers 55, 56, and 57 separated by washers 58 and keyed or otherwise fixedly secured to said shaft, said hammers being of varying lengths and extending at angles with respect to each other to form the shredder head (c). Mounted intermediate disk 49 and ring member 50, their outer ends normally adjacent the outer edges of said disk and ring, are a plurality of equi-spaced fan or blower blades 59 formed with parallel right angle flanges 60, one of said flanges being secured to disk 49 by two bolts 61 and the other similarly secured to ring 50. In the present instance each of said flanges is formed with four apertures 62 which permits said blades to be adjusted inwardly or outwardly with respect to the circumferential edge of the rotor as shown in dotted line at 63 in order to control the air flow through screen (b), passing 48, horizontal discharge section 22, and blower pipe (a) according to the particular operating requirements. It will be observed that these blades, in the present instance four in number, additionally act as reinforcing means for the rotor sections 49 and 50. At diametrically opposite points spaced from the outer edge of the rotor is a bolt 64 extending through disk 49 and ring 50. A plurality of swinging hammers 65 apertured at one end to receive bolt 64 so that when in extended position the ends of said hammers will project beyond the circumferential edge of the rotor as at 66 when the rotor is in operation. Mounted on said bolt intermediate each of said hammers is a spacer washer 67. In the present instance there are two series of these hammers including nine in each series.

On one end of said shaft 48 adjacent opening 21 is suitably mounted a worm 68 adapted to mesh with worm gear 69 mounted on conveyor drum 10 over which is adapted to travel conveyor belt 11 extending at right angles to opening 21 and adapted to deliver thereto material to be cut by rotor C. Overlying the end of conveyor belt 11 is a feed guide trough 72, one end suitably supported adjacent to and conforming to the width of said opening 21, and the other end conforming to the width of conveyor belt 11 and supported by brace 73 with its upper end secured to member 72 adjacent its outer end and its lower end secured to side 1 by bolt 5. The other end of shaft 48 has suitably mounted thereon pulley 74 keyed or otherwise suitably secured thereto which is adapted to be driven by belt 75 from an engine or a suitable source of power not shown.

While the operation of the device would seem to be clear from the above description, it might be well to further state that the material to be acted on by the device when being operated as a hammer mill is fed to opening 21 by conveyor 11 and as it enters said opening is cut by the cutter knives and coming into contact with the shredder head is broken up or further reduced and thrown against the screen where the swing hammers reduce it to the degree of fineness to be blown through the screen by the air produced by the fan blades, then discharged from said casing through the horizontal discharge section 22, and carried by said air blast through blower pipe (a)

into hopper 26 for delivery to a proper container as desired.

To convert the device from a hammer mill to a silage cutter readily without the necessity of removal of bolts and the like, it is only necessary to open the top section 8, remove therefrom screen section 42 and remove from the bottom section screen section 41, close the top and secure by bolt 16, whereupon the machine is converted from a strictly hammer mill type of machine into a silage cutter and blower machine, the length of cuts of the material as it is fed to the machine being regulated by the speed of the conveyor, as will be well understood.

From the above it is apparent that a convertible hammer mill and silage cutter machine has been formed with axially positioned rigid hammers and cooperating circumferentially mounted swinging hammers, adjustable channel blower blades, a horizontal discharge by virtue of which a greater screen area is effected thereby increasing the capacity of the machine, and a casing and screen structure permitting ready accessibility to the interior of the rotor and effecting practically instant conversion from a dry material mill to a silage cutter, said extra screen area, shredder head structure and ball bearing mountings effecting a reduction in horsepower requirements per ton of materials ground or cut, said device comprising few parts, compact in form, manufacturable at a minimum of cost, and efficient for the purposes intended.

Although in practice it has been found that the form of the invention illustrated in the accompanying drawings and referred to in the above description as the preferred embodiment is the most efficient and practical, yet realizing that conditions concurrent with the adoption of the invention will necessarily vary, it is well to emphasize that various minor changes in details of construction, proportion and arrangement of parts, may be resorted to within the scope of the appended claims without departing from or sacrificing any of the principles of this invention.

Having thus described the invention, what is desired protected by Letters Patent is as set forth in the following claims:

1. A feed material convertible hammer mill and silage cutter including a sectional hinged casing having inlet and outlet openings, each section having mounted therein a detachable screen section so arranged with respect to said casing as to form a discharge passage communicating with said outlet when the casing is closed, a rotatable member journaled within the casing and constituting a combination cutter and hammer, said member including a drive shaft, a disk secured to the shaft, a cutter supporting ring adjacent the inlet opening, spacer rods interconnecting the disk and ring adjacent their peripheries, knife means mounted on and connected to opposite points of the ring for cutting the material as it is fed through said inlet opening, reducing means carried by said spacer rods, adjustable fan blades interconnecting said disk and ring adjacent their peripheries at diametrically opposite points adapted to propel the material through said screen and passage, and hammer means mounted on said drive shaft intermediate said ring and disk rigidly secured to said shaft.

2. A feed material convertible hammer mill and silage cutter including a hinged casing section having a sectional screen spaced from said casing to form a discharge passage, a horizontal out-

let formed in the lower section and forming a continuation of said discharge passage, an inlet opening formed in the side of said upper section, a rotatable member journaled within the casing and constituting a combination cutter and hammer, said member including a shaft, a disk rigidly connected to the shaft, a cutter supporting ring, spacer rods interconnecting the disk and ring adjacent their peripheries, material reducing hammer units mounted on said spacer rods, each unit comprising a plurality of swinging hammers, a cutter connected to the ring at opposite points and operative adjacent said inlet opening for cutting the material fed therethrough, a series of rigid hammers fixedly mounted on said shaft adapted to coact on said cut material midway of said ring and disk and tending to direct the same into the path of said hammer units, and a plurality of radially adjustable fan blades interconnecting said ring and disk adjacent their peripheries, whereby the air blasts adapted to propel the reduced material through the screen and passage may be varied in accordance with operating requirements.

3. A convertible hammer mill and silage cutter including a casing, a rotatable member journaled within the casing constituting a combination cutter and hammer, said member including a shaft, a disk rigidly mounted on the shaft, a cutter supporting ring, spacer rods interconnecting the disk and ring at spaced points adjacent their peripheries, swinging hammer units mounted on said spacer rods, a plurality of fan blades interconnecting said ring and disk adjacent their peripheries and radially adjustable with respect thereto, a cutter connected to the ring at opposite points, a shredder head material reducing means rigidly mounted on said shaft intermediate said disk and ring, said casing including a lower section formed with an outlet opening and a hinged upper section formed with an inlet opening at right angles to said ring, coacting screen means carried by said casing sections adapted to form a discharge passage partially surrounding said rotatable member and communicating with said outlet opening.

4. A feed material convertible hammer mill and silage cutter comprising a sectional hinged casing having inlet and outlet openings, a rotatable member journaled within the casing and constituting a combination cutter and hammer, said member including a shaft, a disk keyed to the shaft, a cutter supporting ring, spacer rods interconnecting the disk and ring adjacent their peripheries, a plurality of hammers pivotally mounted on said spacer rods, a cutter supported by said shaft and ring, and operative adjacent to said inlet opening, said cutter being formed in two sections, their outer ends being connected to the ring at opposite points and their inner ends fixed to said shaft, a sectional foraminous partition curved about the center of rotation of the rotatable member adjacent its peripheral edge to form an exhaust passage connecting with said outlet, a plurality of fan blades interconnecting said ring and disk adjacent their peripheries and radially adjustable with respect thereto, a series of hammers keyed in spaced relation to said shaft midway of said disk and ring so as to permit the cut material to pass from the inlet opening over and toward said disk and adapted to direct said material into the path of said first mentioned hammers, conveyor means operatively connected to said rotatable member for feeding the material thereto, and means for driving said member.

5. A convertible hammer mill and silage cutter comprising a rotor including spaced disk and ring members, series of spaced swinging hammer units mounted intermediate and attached to said disk and ring adjacent their peripheries and in circumferential spaced relation, a plurality of fan blades interconnecting said disk and ring and radially adjustable with respect to their peripheries, a drive shaft on which is rigidly mounted 10 said disk, a shredder head material reducing means comprising rigid hammer elements angu-

larly and fixedly mounted with respect to each other on said drive shaft centrally of said disk and ring, a casing adapted to embrace said rotor formed with an inlet and an outlet opening, cutter means carried by said ring member, and detachable coating screen means carried by said casing adapted to form a discharge passage partially surrounding said rotor and communicating with said outlet opening.
